[57] **CLAIM**

The ornamental design for a hub unit for the rear wheel
of a geared bicycle, as shown and described.

DESCRIPTION

FIG. 1 is an isometric view of a hub unit for the rear
wheel of a geared bicycle;
FIG. 2 is a side elevation view thereof, the opposite side
being a mirror image of that shown;
FIG. 3 is a left end elevation view thereof; and,
FIG. 4 is a right end elevation view thereof.

FIG. 1.FIG. 2.FIG. 3.FIG. 4.
